ELI BROTHERS, OF LYNN, MASSACHUSETTS, ASSIGNOR TO UNITED SHOE MACHINERY COMPANY, OF PATERSON, NEW JERSEY, A CORPORATION OF NEW JERSEY.

PULLING-OVER AND LASTING MACHINE.

1,135,947.

Specification of Letters Patent. Patented Apr. 13, 1915.

Application filed June 7, 1906. Serial No. 320,610.

To all whom it may concern:

Be it known that I, ELI BROTHERS, a citizen of the United States, residing at Lynn, in the county of Essex and Commonwealth 5 of Massachusetts, have invented certain Improvements in Pulling-Over and Lasting Machines, of which the following description, in connection with the accompanying drawings, is a specification; like reference 10 characters on the drawings indicating like parts in the several figures.

This invention relates to machines for working uppers over lasts and has for its object to provide a machine by which in successive 15 operations a shoe upper may be "pulled-over" or drawn into preliminary position and adjusted on the last, and then "lasted" or finally conformed to the shape of the last. It has heretofore been the practice to pull-over a shoe by hand or by a 20 pulling-over machine and thereafter to last the shoe in a lasting machine.

The present invention combines in one machine provision for pulling-over the shoe 25 and provision for lasting the shoe.

This invention has the advantage of reducing the number of machines and independent operations required for the manufacture of a shoe, thus economizing time and 30 factory space and saving at least one handling of the shoe.

Another advantage of this invention is that the lasting of the shoe may be performed immediately after the pulling-over 35 operation and it is, therefore, unnecessary to secure the upper by temporary fastenings for holding it between the pulling-over and lasting operations as has heretofore been necessary.

40 The invention has numerous other advantages which will be understood by those familiar with the manufacture of shoes, some of which advantages will be hereinafter pointed out.

45 The illustrative machine herein described and shown is a modification of the machine shown and described in my co-pending application Ser. No. 441,126, filed June 20, 1904, which is a continuation of this present 50 application so far as the two applications disclose common subject-matter, and the claims to features of invention which are common to the two applications are to be found in said application Ser. No. 441,126.

55 A feature of the invention to be protected

in this application consists in the combination with pulling-over means and opposed shoe abutting or supporting means, of means arranged for movement, after the upper has been pulled, in a plane substantially parallel 60 with the shoe bottom into contact with the top face of the shoe. This means is herein shown as embodied in a rest arranged to engage the top face of the shoe, that is, the face opposed to the shoe bottom, and to slide 65 automatically toward the instep of the shoe, with or without means to hold the rest from such sliding movement during the pulling-over operation. In a machine organized as suggested the rest so movable may serve two 70 purposes of which advantage is taken in the use of the present machine. The first is that of sustaining the shoe against displacement during subsequent operations thereon such, for example, as the insertion of tacks into 75 the shoe bottom. During the pulling-over it is advantageous to have said sustaining means out of the way so that the top face of the shoe is the more readily observable by the workman. The other purpose, which 80 may be either additional to or alternative with that first mentioned, is to present a gage extending transversely across the machine and the shoe and with reference to which the position of the tip seam of the 85 shoe upper may be compared.

Another feature of this invention is found in the provision, in a machine in which the last is moved away from the grippers to stretch the upper, of tack and driver guides 90 movable, after the stretching operation, into the space previously occupied by the last to position the tacks relatively to the bottom of the shoe. This movement of the guides is shown as a swinging movement and advantageously takes place in a direction lengthwise of the shoe.

The foregoing features which are to be claimed will now be described in connection with the accompanying drawings, necessary 100 explanation being made in such description of the general organization and construction of the machine, including many features which are claimed in said continuing application.

105 In the drawings which illustrate a preferred embodiment of the invention, Figure 1 is a side view of the upper portion of the machine; Fig. 2 is a front view of the upper portion of the machine; Fig. 3 is a 110

detail perspective view of the lower portion of the machine, showing the operating treadles; Fig. 2 is a horizontal section on line 4—4, Fig. 1, showing the several parts 5 of the machine in position for receiving a shoe. A shoe is shown in section with the upper in position to be gripped; Fig. 5 is a sectional view through the grippers and the shoe in the same plane as Fig. 4, but 10 showing the relative position of the parts after the upper has been pulled; Fig. 6 is a view similar to Fig. 5, but in substantially the plane of the tack drivers, showing the position of the several parts including the toe rest and wipers while the lasting of the shoe is being performed and illustrating the operative position of the tack guides; Fig. 7 is a perspective view of one section of the grippers; Fig. 8 is a perspective view of one section of the lasting plates or wipers; Fig. 9 is a perspective view, partly in section, of one of the tack driving mechanisms; Fig. 10 is a section on line 10—10 of Figs. 1 and 9, showing a detail of the tack driving mechanism; Fig. 11 is a view from the plane of the line 11—11, Fig. 5, showing in section the grippers and the abutment for the bottom of the last and illustrating in dotted lines a movement which may be given the 20 last with relation to the gripped upper for relatively adjusting the last and the toe tip seam of the upper; Fig. 12 is a side elevation, partly in section, showing the position of the parts when an upper has been pulled and illustrating the means for imparting to the last a longitudinal movement for thrusting the last forwardly into the pulled upper; Fig. 13 is a section of the grippers and last and illustrates by dotted lines a tipping movement which may be imparted to the last for tightening the upper over the top of the last; Figs. 14, 15, and 16 illustrate in detail the successive positions which may be assumed by the parts in lasting the upper on the fore part of a shoe; Fig. 17 is a perspective view, partly in section, of the fore part of an assembled shoe, and illustrates the position of the upper on the fore part of a shoe ready to be presented to the machine; Fig. 18 is a perspective view of the fore part of a shoe after having been pulled-over and lasted by the machine.

The head 2 of the machine is adjustably supported by a suitable base at the right elevation for the shoe being operated upon to be conveniently examined for determining the relative position of the last and the lines of the upper and particularly in convenient position for the operator to observe the position of the toe tip seam and lace opening with relation to the last in order that these lines of the upper may be properly located and the seam of both shoes of each pair be arranged in the same relative position. The head provides a bearing for the fulcrum pin 25

4 of bell-crank levers 6 having horizontal arms connected by a forked rod 5 to a treadle 7. The vertical arms of the bell crank lever 6 are secured by pin and slot connections to horizontally movable plungers 8 mounted in suitable guides in the head. To the front ends of each of the plungers 8 is rigidly connected one of the two sections of the movable member 10 of the grippers. The co-operating fixed gripper member 12 is also formed in two sections and is rigidly connected, as indicated at 14, to a plate 15 fixed to the head. Preferably the gripper members are longitudinally curved as indicated in Figs. 2, 7, and 11 to 30 adapt them to receive the edge portion of the upper material of the shoe from one side of the fore part of the last around the toe to the other side of the last, whereby the entire end portion of the upper is acted upon by the grippers simultaneously.

The edge portion of the fore part of a shoe upper assembled upon a last flares outwardly from the sides of the last, as shown most clearly in Fig. 17, and preferably the 35 grippers are formed with a curvature materially greater or of longer radius than the curvature of the end portion of a last, as may be seen from Fig. 11, whereby the grippers are adapted to receive readily the 40 outwardly flaring edge portion of the upper. This arrangement enables the upper to be easily inserted in the grippers when the shoe is presented to the machine and insures that the upper will be held out of contact with the sides of the last when the last and grippers are relatively moved for pulling the upper. This provision for holding the upper away from the sides of the last enables the last and upper to be relatively 45 adjusted with greater facility, as will be more fully explained. The sectional gripper jaws are so constructed and arranged that they may be readily disconnected from their supporting and operating mechanism 50 and removed from the machine to permit jaws of the shape required for lasts of different contours to be inserted in the machine. An abutment 20, against which the bottom of the last or the innersole thereon 55 is rested, is mounted in the head 2 in position to engage the fore part of the last. The pulling of the upper is effected by a relative movement of this abutment and the grippers and as herein shown the abutment 60 is moved while the grippers are held stationary after having clamped the stock. To this end the abutment 20 is mounted for longitudinal movement in the head and is attached at its rear end by a pin and slot 65 to the vertical arm of a bell-crank lever 22. The horizontal arm of the bell-crank lever is connected by a rod 24, movable through a guide 26, with a foot treadle 28 by which 70 the plunger is actuated.

The parts of the machine are so constructed and arranged, as will be observed from Figs. 1, 2, and 5, that the last may be moved in various directions with relation to the 5 abutment 20, such movements being desirable for the purpose of relatively adjusting the last and the upper to locate the important lines of the upper—as, for example, the toe tip seam and the longitudinal lace opening 10 of the shoe—in proper position. For instance, it may be required after the shoe has been drawn about the last to adjust the last and upper transversely of the last. This may be done by moving the last with relation to the abutment about a longitudinal axis, as is indicated in dotted lines in Fig. 5. By this means the upper may be positioned relatively to the last with the lace opening correctly located. Another adjustment 15 which is frequently required is a movement of the fore part of the upper longitudinally about the fore part of the last to straighten the toe tip or locate the two ends of the toe tip seam at the desired relative 20 distances from the toe end of the last. This relative adjustment of the upper and last may be effected by swinging the heel end of the last laterally about the abutment as a center, as indicated in Fig. 11. Sometimes 25 it is desirable to pull the upper over the toe end of the last either more or less than it is pulled over the sides of the fore part and in order to do this the last may be rocked forwardly or backwardly with relation to the 30 abutment as a center, as indicated in Fig. 13. In this figure the dotted lines show the position of a last when the heel end is moved backwardly or toward the machine for stretching the upper over the toe of the last. 35 It is frequently of advantage to strain the upper at the sides of the last slightly backwardly for tightening the upper over the instep of the last and in the present machine this can be done by moving the last forwardly into the pulled upper, as indicated 40 in Fig. 12. Preferably means will be provided for actuating the last forwardly and as herein shown this means comprises a heel rest 30 carried by a vertically movable slide 45 32 which is shown as provided with a pinion 34 in engagement with a rack 36 on the head 2.

A handle 38 is provided by means of 50 which the pinion may be actuated for moving the carrier 32. The carrier is provided with a forwardly extending arm upon which is supported a spring-actuated pawl 40, as shown most clearly in Fig. 1, and the shaft of the pinion 34 is provided with a ratchet 55 41 co-operating with the pawl and by means of which the carrier may be locked in the position to which it is elevated. When the pawl is withdrawn from the ratchet the carrier is free to be and in practice will be 60 moved downwardly by gravity. Prefer- 65 ably provision is made for movement of the heel rest 30 with relation to the carrier 32 in order that the position of the rest may be varied to suit the location of the heel ends of differently shaped lasts. To this end 70 the rest is shown as pivotally connected at 42 to a block 44 which is adjustable forwardly and backwardly and may, if desired, be held in adjusted position by a binding screw 46 extending through a slot in a 75 bracket 48. The bracket 48 is mounted in the carrier 32 for sliding movement laterally, whereby the heel rest may be readily positioned to support heel ends of right and left shoes made on crooked lasts. The 80 rocking movements of the last with relation to the abutment 20 for adjusting the last within the upper may be made while the heel rest occupies a lowered position out of contact with the last, or, if desired, any of 85 these movements of the last may be made while the last is supported by the heel rest, the movable connections between the heel rest and its carrier permitting the rest to accompany the heel end of the last in its 90 movements. The heel rest may, if desired, be employed for supporting the last before and during the pulling of the upper by the relative movements of the grippers and abutment, as above described. The rest will, 95 however, preferably be employed to support the last during the lasting of the shoe.

It is to be observed that the movements of the last for adjusting it with relation to the upper as above explained are facilitated and 100 the adjustments more readily secured by reason of the fact that the grippers hold the work away from the side faces of the last as before described and as illustrated in the drawings. This arrangement permits the 105 last to move within the upper without frictional resistance which would be produced if the upper were held by the grippers in engagement with the side faces of the last.

For finally conforming the upper to the 110 last and laying the edge portion of the upper over upon the innersole after the shoe has been pulled-over by pulling the upper over the last and making such adjustments of upper and last relatively as may be necessary to position the upper properly upon the last, lasting plates or wipers 60 are employed. These wipers are arranged for movement lengthwise of the last for laying the edge portion of the upper backwardly 115 over the toe end of the last and are also arranged for opening and closing movement that they may wipe the upper inwardly on the sides of the last as they advance longitudinally over the last. As herein shown, the wipers are carried by wiper plates 62, see Fig. 8, which are movable in a recess formed for them between the plate 15 and the plate 63, both of which plates are rigidly attached to the head 2. The wipers are piv- 120 125 130 135

totally connected to the lower ends of links 64 by which they are suspended from a cross head 66 having a guide rib 68, see Fig. 2, located in a vertical guideway in the head 2. 5 The cross head 66 is connected at 70 with a lever 72 which is joined by a link 74 to the frame of the machine and has a handle by means of which the cross head and the wipers may be vertically moved. The lever is 10 provided with a spring pressed pawl for engaging a ratchet 75 on the head and a finger lever 76 secured to the handle of the lever is connected with the pawl for withdrawing it from the ratchet. The connections 15 thus far described operate to move the wipers lengthwise of the last. For the purpose of giving them closing and opening movements transversely of the last for wiping the upper inwardly from the sides of 20 the last and then withdrawing, the wipers are connected by links 78 with the stationary plate 63. The links are so arranged that the wipers will be forced inwardly for carrying them transversely over the shoe as 25 they are advanced lengthwise of the last. Any other suitable means for actuating the wipers may be substituted for the means just described.

The heel rest 30 will preferably be employed for supporting the last against longitudinal movement by the endwise thrust of the wipers. A toe rest is provided for supporting the last against the outward pressure of the wipers upon the bottom of 35 the shoe as they are moved for laying the upper over the innersole. The toe rest is preferably movable in a plane approximately parallel to the shoe bottom from an inoperative position, where it does not interfere with the insertion of the shoe and the movement of the last for adjustment with 40 relation to the upper, into an operative position, where it will engage the top face of the fore part of the shoe and support the last. This rest is herein shown as a padded block 80 carried by a vertically movable 45 slide 82 which is guided by undercut ribs on the plate 63, as shown most clearly in Fig. 4. A spring-pressed locking pin 84 is 50 provided on the plate 63 for engaging a recess in the slide 82 to hold the slide in the raised position shown in Figs. 1 and 2 where the toe rest is out of operative relation to the shoe.

55 In the construction shown the toe rest 80 is provided with a stem 86 which is adjustably secured in a forwardly and downwardly extending arm of the slide 82. The stem is shown as provided with a groove 60 into which turns a binding screw 88 by means of which the toe rest is held in adjusted position with relation to the plane of the top of the last and is restrained from rotation. In practice the toe rest will 65 preferably be held in its raised position, as

shown in Figs. 1 and 2, during the pulling over operations and when the shoe is about to be lasted by the actuation of the wipers the stop will be withdrawn to permit the toe rest to descend into engagement with 70 the top face of the fore part of the shoe. The toe rest will preferably be so adjusted with relation to the plane of the top face of the shoe that as it descends it will engage the inclined front end of the last—as, 75 for example, in the position shown in Fig. 14. It will be understood that the position to which the last will have been moved by the abutment 20 in stretching the upper will vary somewhat in different shoes and by 80 arranging the toe rest to engage the inclined portion of the end of the shoe, as shown, no adjustment of the toe rest in its slide will ordinarily be required on account of the 85 position of the shoe. The toe rest will preferably be located in the slide 82 with reference to the plane of the wipers so that when the rest is lowered into operative position it will strike the usual inclined face of the 90 front end of the last, as illustrated in Fig. 90 14, and will press downwardly by gravity along this face thus tending to wedge or force the last rearwardly against the wipers as the wipers are closed for laying the upper over the innersole. In practice the 95 abutment 20 will preferably be retracted as the wipers are moved into operative position so that the toe rest may be free to force the last firmly against the wipers. If, as may frequently happen, the last is 100 moved so far for stretching the upper that the bottom of the last is carried forwardly beyond the plane of the wipers, as shown, for example in Fig. 14, the toe rest will 105 force the last backwardly against the wipers when the abutment 20 is retracted, as illustrated in Figs. 15 and 16. This arrangement enables the wipers to act effectively notwithstanding different initial positions of the last with relation to the plane of the 110 wipers.

For inserting tacks the machine herein illustrated is provided with two tack driving mechanisms which are independent in their construction, but are arranged to be 115 operated simultaneously. To this end the machine head supports a rockshaft 90 to one end of which is pinned a bell-crank lever 91 connected by a rod 92 with a foot treadle 93. The vertical arm of the bell-crank lever 120 is secured by a pin and slot connection to the driver bar 94. The end of the rock-shaft 90 opposite to that on which is mounted the bell-crank lever 91 carries an arm 951 corresponding in position and function to the 125 vertical arm of the bell-crank lever and united by a pin and slot connection to the driver bar 94 of the second tack driving mechanism. The tacking mechanisms are alike and the detail construction thereof is 130

shown in Fig. 9. As will be seen from this figure the mechanism includes a guide block 95 through which the driver bar 96 is guided and which carries in this embodiment of the invention means for holding and advancing a tack strip, i.e. advancing means operated to present a tack automatically in alignment with the driver during each back stroke of the driver bar. To this end the 10 front portion of the guide block 95 is provided on its outer side with a guide 97 for a tack strip 98. The guide block also is provided with an outwardly extending sleeve 100 in which is mounted for endwise movement a rod 102 connected at its outer end by a plate 104 with a ratchet bar 106 having a blade extending through slots in the guide 97 and in the guide block 95 as shown in Fig. 9, and provided with teeth 20 for engaging the shanks of tacks on the tack strip. A spring 108 normally presses the rod 102 in the direction for moving the ratchet bar to advance the tack strip while the inner end of the rod projects into the 25 guide block 95 and stands in the path of a cam surface 110 on the driver bar 94. With this construction advance movement of the driver bar forces the rod 102 outwardly and causes the ratchet bar to be drawn backwardly over the tack strip. When the 30 driver bar is retracted the spring 108 moves the rod 102 and the ratchet bar to feed the tack strip forwardly a distance equal to the space between two tacks in the tack 35 strip. In this way the tacks are automatically presented in position to be driven. As herein illustrated it is contemplated to drive one tack at each side of the fore part of the shoe and to employ these tacks primarily as anchoring tacks for a binder of 40 wire or tape by which the upper about the fore part of the shoe is secured in lasted position. This binder holds the upper material against the lip of the innersole and 45 in the angle of union between the lip and the feather-edge of the innersole. It is desirable that the anchoring tacks be driven approximately in this angle of union in order that the end portions of the binder, 50 which also serve as securing means for the portion of upper through which they are driven may fasten the upper at the right places.

55 The tack driving mechanism should therefore, be spaced the right distance apart in the machine to insert the tacks in the angle of union on the opposite sides of the shoe, and for operating upon shoes of different 60 widths it is desirable to be able to adjust the tack driving mechanisms toward and from each other. To this end the guide blocks 95 are provided on their lower faces with guide ribs 112 as seen most clearly in 65 Figs. 1 and 9 and the head of the machine is

provided with a bracket 114 having a groove extending transversely of the machine to receive the rib 112. The bracket has a slot for receiving adjustably a screw 115, as shown, in Fig. 10, by which the guide block 70 may be secured in different adjusted positions for spacing the driven tacks in accordance with the width of the shoes being pulled-over and lasted. The vertical arm of the bell-crank lever 91 and the corresponding arm 95 on the opposite side of the machine are forked at their upper ends, as shown in Fig. 4, and the branches of the forks are separated far enough to permit the adjustment of the tacking mechanisms 75 above described.

It will be understood that inasmuch as the last is moved away from the grippers for stretching the upper the shoe is by this movement also carried away from the tacking mechanism. It is desirable in driving the tacks that the tack be guided substantially to the plane of the stock in which it is inserted and in order to do this tack guiding means is provided which is movable to permit the shoes to be positioned initially in the proper relation to the grippers and which will, after the shoe has been moved away from the grippers, guide the tack substantially to the plane in which the shoe bottom 90 is then located. While different constructions of tack guiding means may be employed for this purpose the present machine is shown as provided with pivoted tack guiding means adapted to be turned into a position out of alignment with the driver when the shoe is presented to the grippers and to be moved into an operative position in alignment with the tack drivers when the tacking mechanism is to be actuated. These 95 tack guides are shown as tubes 120 hinged to the front ends of the guide blocks 95, as shown in Figs. 4 and 9. The tack guides may be turned downwardly as shown in Figs. 1, 2, and 4 before the shoe is presented to the machine and they may remain in this position where they are out of the way of the operating parts of the machine until the pulling-over and lasting operations have been completed and may then be turned up into operative position in alignment with the drivers as shown in Fig. 6. The two tacks will then be inserted simultaneously by depressing the foot treadle 93. The treadle rod 92, and likewise the treadle rods 100 105 110 115 120 5 and 24, are provided with a returning spring 8, Fig. 3, to elevate the treadle and restore the parts connected to the rods to their normal positions.

In the use of the machine a last with an 125 upper and innersole properly assembled thereon is presented to the machine by placing the outstanding edge portion of the fore part of the upper within the grippers. Preferably the abutment 20 occupies nor-

5 mally a position to serve as a rest against which the innersole on the bottom of the last will be pressed in presenting the shoe to the machine.

10 5 The operator will arrange the upper within the grippers with the tip line or seam in correct relation to the last. He is guided in doing this by the curved grippers which are in practice preferably long enough so that their lower ends reach to the tip seam. Any suitable tip position indicating formation of the grippers may be used to guide the operator in placing the upper in the machine before the grippers are closed. For example, the angular front edge of the outer gripper jaw may be considered as an index line with relation to which the tip line may be positioned. The operator can position the seam straight by locating the ends of the seam in the same or desired different relation to the ends of the grippers and he positions the seam for the right length of tip by locating the seam ends more or less near to the ends of the grippers. The latter 25 movable heel rest which supports the shoe during the upper positioning and upper pulling operations facilitates correct adjustment or initial positioning of the tip seam on crooked lasts for by positioning the heel rest at the left side or the right side of the median line of the machine it will support a left shoe or a right shoe on a crooked last with the fore part in similar relation to the grippers and allow of the tip of the right and the left shoe being positioned similarly in the grippers. This positioning of the tip seam and, in fact, the entire pulling-over and lasting operation is facilitated by the fact that the shoe is arranged in the 30 machine with relation to the operator with the toe end pointing away from him and substantially perpendicular to his line of vision. This is a position in which a critic holds a shoe to judge of its symmetry and 35 the correct proportions of its parts and is, in fact, substantially the relation which a shoe on the wearer's foot bears to his line of vision. I believe I am the first to provide for accurately and invariably locating 40 the tip line relatively to the pulling-over devices.

45 The foot lever 7 is first actuated for closing the grippers and then the foot lever 28 is depressed for advancing the abutment 20 to move the last outwardly with relation to the grippers, whereby the upper is stretched simultaneously at the opposite sides and the end of the fore part of the shoe. The form of the grippers insures that in this movement the upper will be drawn between the top face of the last and the grippers without frictional engagement between the sides and edges of the last and the upper. The position of the shoe is such that the operator 50 may observe the work and use his judgment as to the extent to which the upper should be stretched and when the treadle 28 has been depressed for pulling a particular upper as much as is required the operator, having observed the position of the toe tip seam and other lines of the upper with relation to the last, may move the last for properly adjusting it within the upper. For example, he may swing the last laterally as indicated in Fig. 11 to straighten the toe tip 55 seam or he may turn the last sidewise as indicated in dotted lines in Fig. 5 to adjust the last transversely in the upper. If the toe tip seam is found upon inspection to extend in a curved line rather than in a right line the last may be moved backwardly or forwardly as indicated in Fig. 13 to pull or slacken the upper over the toe end of the last for straightening this seam, and if desired the last may be moved upwardly as shown in Fig. 12 for thrusting it farther into the pulled upper and thus tightening the upper over the fore part of the last and about the instep of the last. For effecting this latter movement the heel rest may be 60 actuated by the hand lever 38. When the upper has been satisfactorily stretched and the proper position of the upper with relation to the last secured as is required in the pulling-over operation the toe rest will be 65 released and permitted to move into operative position preparatory to the lasting operation. The wipers will then be actuated by manipulating the hand lever 72 and as the wipers force the upper over the last bottom pressure on the foot treadle 28 will 70 preferably be relieved to permit the abutment 20 to be retracted enough to allow the toe rest to press the shoe toward the wipers, and pressure upon the foot treadle 7 will 75 also be released gradually to permit the grippers to open for allowing the upper to be pulled from between them by the advancing wipers. These operations having 80 been completed the swinging sections of the tack tubes will be moved into operative position and the foot treadle 93 depressed for actuating the drivers to insert the tacks. The shoe may then be taken from the machine and a binder of wire or tape put in 85 place to retain the upper in overworked position.

90 The claims to the improvements in methods of making shoes herein disclosed are to be found in my co-pending application Ser. No. 851,194, filed July 15, 1914.

95 Having indicated the nature of the invention and fully explained one construction embodying the same, I claim as new and desire to secure by Letters Patent of the United States:—

100 1. In a machine for working an upper over a last in which the last is positioned with its toe end uppermost, the combination with means for pulling the upper over the 105

- toe portion of the last, and wipers for laying the upper over the last bottom, of a rest arranged to engage the top face of the shoe, a carrier by which said rest can slide by 5 gravity from a position above the toe of the shoe downwardly toward the instep of the shoe for the purpose described, and means for locking it in its elevated position, substantially as described.
6. A pulling-over machine having, in combination, means for working an upper over a last, means for supporting the shoe with its toe end uppermost and the top face of the shoe observable by the workman; a vertically movable slide, a toe rest on the slide, means for securing the slide in an operative position, and means for guiding the slide to position the rest in operative relation to the top face of the shoe when the 15 slide is released.
7. A pulling-over machine having, in combination, mechanisms for working upon a shoe, means for supporting the shoe for an initial operation upon it, a rest occupying 20 normally a position forwardly beyond the toe of the shoe, and means for directing movement of said rest lengthwise of the shoe into operative engagement therewith for supporting the shoe for a later operation 25 upon it.
8. A pulling-over machine having, in combination, pulling-over means, means to support the last against the action of the pulling-over means, means to drive tacks into the 30 shoe bottom, a rest occupying normally a position forwardly beyond the toe where it is out of the way of inspection of the shoe during the pulling-over operation, and guides for directing movement of the rest lengthwise of the shoe into engagement with an inclined portion of the top face of the shoe 35 whereby it is self-adapting for supporting shoes of different thickness against the operation of the tacking means.
9. A pulling-over machine comprising shoe supporting means, pulling-over means, and means arranged for movement in a plane substantially parallel with the shoe bottom, after the upper has been pulled, 40 into and out of contact with the top face of the shoe in the region of the tip seam.
10. A pulling-over machine having, in combination, pulling-over means, means to support the last against the action of the 45 pulling-over means, and means occupying a position forwardly beyond the toe of the shoe during operation of the pulling-over means and guided for movement lengthwise of the shoe into pressing engagement with 50 the top face of the forepart of the shoe, 60 substantially as described.
11. In a machine of the class described, the combination with mechanisms for working an upper over a last, of tack-driving mechanism which as a whole is secured in a fixed 65 position and comprises a tack guide movably supported to allow it to be positioned out of the way of the shoe during the over-working operations.
12. A pulling-over machine having, in combination, means for pulling-over an upper, means for working the upper into lasted relation to a welt shoe innersole, and anchor tack driving means occupying constant positions transversely of the shoe near 70 each lateral side of the shoe during the pulling-over operation and including tack and driver guides which are movable lengthwise of the shoe into position to guide and locate the anchor tacks after the upper has been 75 overworked.
13. A pulling-over machine having, in combination, means for pulling-over an upper, means for working the upper into lasted relation to a welt shoe innersole; and 80 an anchor tack driving mechanism fixed near one lateral side of the shoe and comprising a guide block and a driver and tack supplying mechanism co-operating therewith, and a driver and tack guide pivoted 85 relatively to the guide block for movement out of alignment with the driver and away from the plane of the shoe during the pulling-over operation, said guide being movable into operative relation to the driver and 90 the shoe for the anchor tack inserting operation.
14. A pulling-over machine having, in combination, pulling-over grippers, a tacking mechanism, a shoe bottom abutment, and 95 means for actuating the abutment to force the last away from the grippers to effect the stretching of the upper, said tacking mechanism including a tack and driver guide having an end section which is mounted to 100 swing out of the way to permit the shoe to be initially positioned adjacent to the grippers, said section being movable, after the last has been forced away from the grippers, into the space formerly occupied by 105 the last to guide the tack to the shoe bottom.
15. In testimony whereof I have signed my name to this specification in the presence of two subscribing witnesses.

ELI BROTHERS.

Witnesses:

ARTHUR A. RUSSELL,
CHARLES E. GRUSH.

It is hereby certified that in Letters Patent No. 1,135,947, granted April 16, 1915, upon the application of Eli Brothers, of Lynn, Massachusetts, for an improvement in "Pulling-Over and Lasting Machines," an error appears in the printed specification requiring correction as follows: Page 5, line 55, for the word "mechanism" read *mechanisms*; and that the said Letters Patent should be read with this correction therein that the same may conform to the record of the case in the Patent Office.

Signed and sealed this 5th day of October, A. D., 1915.

[SEAL.]

R. F. WHITEHEAD,

Acting Commissioner of Patents.
